UNITED STATES PATENT OFFICE.

JAMES ALLINGHAM, OF CHICAGO, ILLINOIS.

HYDRAULIC AND AUTOMATIC WASTE VALVE FOR VESSELS.

Application filed January 7, 1925. Serial No. 976.

This invention relates, generally, to waste valves for liquid containing vessels, but has particular relation to that type of valves employed in connection with bath tubs and the like, and embodies improvements on or over the structure or construction disclosed in Letters Patent No. 1,049,828, granted to me on the 7th day of January, 1913, for improvements in hydraulic and automatic 10 waste-valves for vessels.

The present invention has, as one of the main objects thereof, the provision of a waste-valve, more particularly for bath tubs, but not restricted thereto, which shall be of such construction, arrangement and combination of its parts as to conform to the new order or style in architecture relative to bath tubs, known as the "built-in" type, in which the fixtures of the tubs are concealed, 20 and so as to comply with the law and regulations of the sanitary boards of many cities, which require that traps or water seals in connection with the waste or drain pipes of bath tubs, as shown in Fig. 1 of the drawings, of my above mentioned patent, shall not be employed.

Another and important object of my present invention is the provision of means whereby, when the devices are employed in 30 connection with bath tubs of the "built-in" and "fixture-concealed" type, certain parts thereof, those most likely to require cleaning, adjustment and repairs, may be readily removed from their concealed or operative 35 positions and quickly replaced, without interference with the closure for the fixtures.

A further object is to furnish a waste valve for vessels that will act or waste automatically at a given pressure of liquid, and which shall have manually operable means 40 for discharging all or any desired amount of liquid from the vessel.

Other objects and advantages of the invention will be disclosed in the following description and explanation, which will be more readily understood when read in conjunction with the accompanying drawings, in which embodiments of the invention are illustrated, it being understood that modifications and changes may be resorted to without a departure from the invention, so long as they fall within the scope of the appended claims forming a part hereof.

In the drawing,—

Fig. 1 is a vertical sectional view of a portion of a bath tub of the "built-in" type,

illustrating sectionally an automatic waste-valve embodying one form of the invention mounted on the tub.

Fig. 2 is a vertical sectional view taken 60 on line 2—2 of Fig. 1 looking in the direction indicated by the arrows.

Fig. 3 is a plan sectional view taken on line 3—3 of Fig. 1.

Fig. 4 is a detached enlarged perspective 65 view of the valve and guiding plunger of the device.

Fig. 5 is an enlarged plan sectional view taken on line 5—5 of Fig. 2 showing means for securing parts of the device to the upper 70 portion of the tub at the overflow opening therein.

Fig. 6 is a view similar to Fig. 1 showing a modified form of the device mounted on a bath tub of the type heretofore in general 75 use, or rather, of the "non-built-in" type.

Fig. 7 is a plan sectional view taken on line 7—7 of Fig. 6, and

Fig. 8 is an enlarged plan sectional view taken on line 8—8 of Fig. 6, showing the 80 details of construction employed in the modified form of the device.

Corresponding numerals of reference refer to like parts throughout the different views of the drawings.

Referring now to Figs. 1 to 5 inclusive of the drawings, the reference numeral 10 designates a portion of a bath tub of the "built-in" type, the line of the closure for concealing the fixtures thereof being indicated at 11 in Fig. 1 of the drawing. The tub 10 is provided in its lower surface near its upwardly extended end wall adjacent the line 11 of the closure for the fixtures with a drain or waste opening 12 and near 90 the upper portion of said wall with an overflow opening 13 both of which openings are by preference circular in shape. The waste opening 12 has fitted therein so as to be about flush at its upper end with the upper 100 surface of the bottom of the tub a short nozzle 14 which is by preference externally screw-threaded to engage the upper end of the L-coupling 15 between which and the bottom of the tub is located suitable packing 105 16 to prevent leakage. The nozzle or member 14 is provided internally with a transversely disposed apertured bar 17 for engagement with the lower end of a screw 18 employed to detachably secure to the mouth 110 of the nozzle or member 14 a perforated strainer 19 which is provided centrally with

2
an opening for the said screw. The overflow opening 13 of the tub has fitted thereto in any suitable manner on the outside of the upwardly extended end wall of the tub an L-coupling 20, which coupling has on its inner surface near its end adjacent the opening 13 a pair of apertured and diametrically disposed lugs 21, see Figs. 2 and 5, for engagement with the inner ends of screws 22 which are employed for securing a perforated bearing member 23 to the upright end wall of the tub over said overflow opening. This bearing member 23 has a centrally disposed hub 24 in which is located a rotary shaft 25 which is provided on its end within the coupling 20 with a crank 26 and on its other end with a handle 27 for use in manually operating the valve when so desired. The screws 22 are extended through suitable openings in the member 23 and as will be readily understood by reference to Figs. 2 and 5 of the drawings, engage the lugs 21 on the coupling 20 so as to securely clamp the members 20 and 23 on the outer and inner surfaces respectively of the upright end wall of the tub around the opening 13 therein, or should it be desired, against packing rings 28 and 29 located at the peripheries of said members around said opening.

Screwed or otherwise fitted at one of its ends into the lower end of the coupling 15 is a horizontally disposed waste tube or pipe 30 to the other end of which the valve casing of the device is connected. This valve casing is, when viewed sidewise, substantially of the shape of a T-shaped coupling; that is, it is provided with three ways or tubular portions which communicate with one another inwardly of their outer ends. One of these tubular portions, which may be termed the inlet of the valve, indicated by the numeral 31, is connected to the waste pipe or tube 30 by means of a coupling 32, while another 33 of these tubular portions or ways which is located opposite the tubular portion or way 31, is connected to a discharge pipe 34 leading to any suitable point of discharge, and may be termed the outlet portion or way. The portions 31 and 33, as is clearly shown in different views of the drawings, are located substantially in a horizontal plane but with the lower portion of the part 33 disposed at a somewhat lower level than the lower portion of the part 31 or inlet. Between the tubular portions 31 and 33 the valve casing is provided with a vertically disposed tubular portion or way 35 which has communication through a pipe 36 with the L-coupling 20 of the overflow opening of the bath tub as will be readily understood by reference to Fig. 1, in which view it will be seen that the lower portion of the pipe 36 is connected to the overflow way or tubular portion 35 by means of a

coupling 37 and that the discharge pipe 34 is connected to the outlet way or tubular portion 33 by means of a coupling 38 of a well known construction and in the usual manner.

The valve casing is provided between its tubular portion or way 35 and the tubular portion or way 31 with a vertical partition 39 which terminates or is provided with a horizontally disposed valve seat 40 located 75 between the partition 39 and the lower portion of the outlet way or portion 33 of the valve casing in such a way that its lower surface will occupy a plane slightly above the inner surfaces of the lower parts of the 80 ways or portions 31 and 33 of the valve casing, which casing is provided below the partition 39 and said valve seat with a pocket having sloping walls. The opening or valve seat 40 is located below the lower end of the 85 pipe 36 so that their axes will be in true alignment.

Located within the valve casing above the seat 40 thereof to co-operate with said seat is a spherical shaped valve 42 which is provided at its upper portion with a vertical extension 43 united to the lower portion of a guide member 44 which is by preference cylindrical in shape or of a shape to correspond with the pipe or conduit 36 in the 90 lower portion of which it is located for vertical movement. This guide member 44 is by preference hollow and has apertures in its upper and lower ends as is clearly shown in Figs. 1, 2 and 4 of the drawings to permit of the free passage of water. The upper end of the guide plunger 44 is provided with an upright extension 45 to which is loosely connected the lower end of a flexible connection 46 such as a chain, the other end of which is loosely connected to the crank 26 on the crank rod or shaft 25 in such a way that by turning the handle 27 on said rod in the proper direction, the valve may be raised from its seat, in which operation it is manifest that the guide plunger 44 will be guided in its movement by the tube 36 which acts in the capacity of a guide for said plunger and the valve as well as a conduit for the overflow water from the tub.

An expansion spring 47 coiled around the crank rod 25 and resting at one of its ends against one end of the hub 24 and at its other end against the crank or arm 26 on said rod will serve to hold the valve and its connected parts in its raised or elevated position as shown by dotted lines in Fig. 2, until it is desired to lower the same, when it is obvious that by turning the handle 27 to its normal position, the valve will be seated by reason of its gravity.

From the foregoing and by reference to the drawings, it will be readily understood and clearly seen that by my improvements I have provided a waste valve mechanism in 130

which the valve will be automatically operated so as to permit water in excess of a predetermined amount to be discharged from the tub or vessel, for it will be understood that a valve with its vertical extension, and guide plunger, of a weight sufficient to be overcome by a predetermined amount of water pressure can be selected and connected to the flexible connection 46, whereby it may be positively or manually operated as above stated. It is further apparent that by my improvements I have provided a structure in which water traps or seals connected with the drain pipes of bath tubs or the like, is eliminated as in the operation of the device, but a small quantity of water, insufficient to seal the valve seat, will accumulate in the pocket 41 below the valve. By removing the screws 22 from engagement with the lugs 21 on the L-coupling 20, it is apparent the bearing member 23 carrying the crank rod 25, connection 46, the valve and its guide plunger can be readily removed, thus permitting said parts to be cleansed or repaired and also allowing the valve casing and tube 36 to be cleansed. By removing the strainer 19 it is obvious that a suitable instrument may be inserted through the nozzle 14, drain pipe 33, into the pocket 41 for the purpose of removing sediment and the like therefrom.

In Figs. 6 to 8 inclusive is shown a modification in the construction of the valve mechanism which is more particularly intended for use in connection with bath tubs of the exposed fixture or heretofore commonly used type. In this modification the valve casing is of the same construction as that shown in Figs. 1 to 3 inclusive and above described, with the exception that the upper end of the vertical tubular portion or way 35 is equipped with an orificed cap 48 screw-threaded therein, said cap having a small guide tube 49 for the flexible connection 46 for the valve and its guide plunger located at its lower end in the opening of the cap and extended upwardly but terminating below the handled crank rod used for manually operating the valve.

This small pipe, besides serving as a guide for the connection 46, also acts as a receptacle for water should the device be manually operated the water would rush into the valve casing and by gravity force the water would rise in said pipe to a given point and then recede. In this modified form of the device a bearing member 23^a for the crank shaft 25 is employed to cover an opening 50 in the upper portion of an end wall of a tub provided for the reception of said bearing member, and this bearing member differs in construction from the one employed in the first above described structure in that it is not intended that the opening 50 shall be employed as an overflow open-

ing. The bearing member 23^a is secured to the end wall of the tub 10 by means of screws 51 inserted through suitable openings in the member 23^a and each engaging a suitable opening in a clamping plate 52 located on the surface of the tub opposite said bearing member or rather on a packing ring 53 interposed between said plates and the outer surface of the tub to prevent leakage. 75

Having thus fully described my invention, what I claim as new and desire to secure by Letters Patent is:

1. A valve of the class described consisting of a casing having an inlet, an outlet 80 and an overflow opening, a tube extended upwardly from said overflow opening, a pipe connected at one of its ends to said inlet and adapted for communication with the waste opening in the lower portion of a 85 vessel, and a valve located in said casing and automatically operated by a predetermined amount of fluid pressure in said vessel, said pipe having a downwardly curved pocket for deflecting the flow of water under the 90 said valve.

2. A valve of the class described consisting of a casing having an inlet, an outlet and an overflow opening, a tube extended upwardly from said overflow opening, a 95 pipe connected at one of its ends to said inlet and adapted for communication with the waste opening in the lower portion of a vessel, a valve seated in the casing and having an apertured guiding and reciprocating 100 means therefor located in said overflow opening and said tube, respectively.

3. A valve of the class described, consisting of a casing having an inlet, an outlet and an overflow opening, a vertical tube 105 connected to the said overflow opening, a pipe connected to said inlet and adapted for communication with the waste opening in a vessel, a valve seated in the casing and means for automatically and manually moving the 110 same, said pipe having a downwardly curved pocket for deflecting the flow of water under the said valve.

4. A device of the class described including in combination with a vessel having an 115 overflow opening in its upper part, a valve casing having a vertically disposed overflow opening and provided with a valve seat within the casing below said opening and having below said valve seat a depending 120 pocket, a vertically disposed tube connecting the overflow opening of the valve casing with the overflow opening of said vessel, a valve cooperating with said seat within the casing and having an upward extension provided with a guide member having a passage therethrough and located in the lower portion of said tube, and means connected to said guide member and extended through said tube and overflow opening of 130

the vessel for the purpose of manually operating said valve.

5. A device of the class described including in combination with a vessel having an overflow opening in its upper part a valve casing having a vertically disposed overflow opening in its upper wall, a vertical tube connecting the overflow opening of the valve casing to the overflow opening of said vessel, a valve seated in said casing and comprising a spherical base and cylindrical and apertured guide member mounted on and above said base and means connected to the said guide member and extended through said tube and overflow opening of the vessel for manually operating said guide member and valve.

6. A valve consisting of a spherical base having a vertical extension thereon and an apertured guide member mounted on said extension and means on said guide member for manual movement of the same.

7. In a device of the class described, a fitting provided with vertical and lateral orifices, a waste valve seated in the vertical orifice for vertical adjustment, means in the lateral orifice communicating with the valve below its seat for automatic adjustment of

the valve and connecting means for manual adjustment of said valve.

8. A waste and overflow valve including in combination a vessel provided with a waste opening and an overflow opening, a tubular body member having a waste opening and an overflow opening and a discharge opening arranged therein, a vertically disposed tube secured in the overflow opening of said body member and having the free end of said tube secured to and registering with the said overflow opening in said vessel, a horizontally disposed tube having one end of said tube secured to and registering with the said waste opening of said body member and having the free end of said tube secured to and registering with the said waste opening in said vessel a horizontally disposed valve seat in said body member, a valve seated thereon and having a depending pocket below the valve seat and a vertically disposed partition adjacent to said valve for directing the flow of water from said vessel against the bottom of said valve which is actuated by a fluctuating quantity of water contained in said vessel.

JAMES ALLINGHAM.
